Ed Steel Jackson,
Attorney

UNITED STATES PATENT OFFICE.

DAVID ROBERT YARNALL, OF PHILADELPHIA, PENNSYLVANIA, ASSIGNOR TO NELSON VALVE COMPANY, OF CHESTNUT HILL, PHILADELPHIA, PENNSYLVANIA, A CORPORATION OF PENNSYLVANIA.

NON-HEATING VALVE HAND-WHEEL.

1,218,032.

Specification of Letters Patent.

Patented Mar. 6, 1917.

Application filed September 8, 1916. Serial No. 118,986.

To all whom it may concern:

Be it known that I, DAVID ROBERT YARNALL, a citizen of the United States, residing at 316 Preston street, Philadelphia, in the county of Philadelphia and State of Pennsylvania, have invented a certain new and useful Non-Heating Valve Hand-Wheel, of which the following is a specification.

10 My invention relates to hand-wheels for steam valves in which it is desirable to attain a maximum of strength with thorough reliability and as much heat insulation as possible.

15 The purpose of my invention is to provide a pair of radially arranged annular rims of different diameter spaced by a relatively thin central perforated web.

20 A further purpose of my invention is to make the outer part of the wheel of girder section with the head or flange upon the inside smaller than upon the outside.

25 A further purpose of my invention is to supply an annular heat distributing ring, or annulus connected with the hub and to provide a larger grasping ring thereabout, spaced therefrom by a circumferentially interrupted web.

30 Further purposes will appear in the specification and particularly in the claims thereof.

I have preferred to illustrate my invention by but one form thereof, selecting one which in practice has proved to be light, 35 strong, a good heat insulator and inexpensive in manufacture and which at the same time well illustrates the principles of my invention.

40 In the drawings, similar numerals of reference indicate like parts.

Figure 1 is a top plan view of the preferred embodiment of my invention.

Figs. 2, 3 and 4 are sections of Fig. 1 upon lines 2—2, 3—3 and 4—4, respectively.

45 The hub 1 contains the usual tapered stem hole 2 and supports the spokes 3. These spokes are shown as extending in radial planes, but at an angle with the radii within these planes, as best seen in Fig. 2, giving 50 room for the valve stem nut below the level of the hand hold.

Instead of connecting the spokes directly with the outer rim, I connect them with an inner rim or annulus 4, of preferably ellipti-

cal cross section and with the major axis of 55 the ellipse (its depth) parallel with the hub axis. I give the annulus 4 considerable body for the purposes of providing strength and of distributing the heat and giving off a large proportion of the heat conducted to 60 it by the spokes 3.

In order that the heat from the annulus 4 may affect the user of the valve as little as possible, I surround it by an outer annulus or rim 5, whose depth (parallel with the 65 axis of the hub) is greater than the depth of the annulus 4 so that the relative projection of the faces of the outer annulus beyond the inner annulus will protect the hands of the user from engaging the more highly 70 heated inner annulus. The two annuli or rims are connected by a preferably radial web 6 perforated as at 7. The outer rim is also shown as of elliptical cross section and the two rims may be considered as forming 75 "heads" or oppositely extending flanges for the web, giving a girder cross section.

I show a large number of perforations in the web to reduce the heat conductivity between the annuli 4 and 5, while maintaining sufficient strength between.

To improve the grasping qualities of the handle, I supply projections 8 about the outer circumference of the rim.

My construction is adapted to be cast and 85 forms its own core. The two annuli make up a composite "rim" of girder section connected with the interior spokes, providing a maximum of strength and convenience and a minimum of heat in the outer part of the 90 rim. The hand hold is raised relatively to the rest of the wheel.

Having thus described my invention, what I claim as new and desire to secure by Letters Patent is:—

1. In a valve hand wheel, a valve wheel having two co-axial, radially-disposed annuli of different depth axially of the wheel, connected by an approximately central apertured web and that annulus which is of 100 greater depth being also of larger diameter than the other, in combination with a hub and spokes connecting the hub and inner annulus.

2. In a valve hand-wheel, a hub, an annulus surrounding the hub, spokes connecting the hub and annulus extending at an angle to the radii of the annulus, a rim out-

- side the annulus in radial line therewith having greater depth axially of the hub than the annulus and an apertured web connecting the annulus and rim.
- 5 3. In a valve hand wheel, a valve wheel having two coaxial annuli of different depth, axially of the wheel, connected by an apertured web to form a beam section, that

annulus which is of greater depth being of the larger diameter and having its outer 10 edge extending farther axially away from the valve than the annulus of lesser depth and diameter, in combination with a hub and spokes connecting the hub and inner annulus.

DAVID ROBERT YARNALL.
